DRESSING FIXTURE FOR CONTOURING
GRINDING WHEELS

Walter Muench, Newark, N. J., assignor to Walter Muench, Incorporated, Newark, N. J., a corporation of New Jersey

Application January 7, 1950, Serial No. 137,321

14 Claims. (Cl. 125—11)

1

This invention relates to fixtures with which to cut, with the aid of a diamond that is mounted in a tool-shank, concave and convex radii in the circumferential part of a grinding wheel.

In order to grind a precision concave or convex forming tool-bit which is to be used in a lathe or so-called screw-machine, the grinding wheel must be so trimmed with a diamond-tool that it imparts the shape required for the wheel to grind clearance on the forming tool-bit.

To produce that clearance-cutting effect on the grinding wheel, the diamond-tool holding fixture must be tilted from 2 to 7 degrees, depending on the clearance required, which differs, when the parts to be so machined are made from aluminum, brass, bronze, copper, iron, magnesium, tool-steel or stainless-steel etc., etc.

All fixtures now in use with double-end bearing supports can be tilted only by putting a piece of flat stock of varying thickness under one end of the fixture.

By this procedure the holding power of the magnetic chuck, on which the fixture is held in position, is impaired to such an extent that the fixture must be packed up on both sides with magnetic parallels to prevent shifting of the fixture while in operation under the grinding wheel.

However, in spite of any precautions taken with parallels, the danger remains that the fixture be lifted up if inadvertently the grinding-wheel should be fed down a trifle too fast toward the diamond-tool that is cutting the required contour into the periphery of the grinding wheel.

Another disadvantage in the old style radius-dresser is the utter impossibility to apply a sine-bar to do modern high-grade precision work by a safe, secure and efficient method.

To overcome the foregoing described faults is the purpose of the invention presented herein.

For a clear understanding of the many new features offered in this invention and to all persons versed in the art to fully comprehend the advances made in mechanical functions and the consequently greatly enhanced operational facilities, drawings, depicting a preferred form have been annexed in which:

Fig. 1 is a front-view of the fixture, constituting basically a so-called radius-dresser.

Fig. 2 is a top-view of the fixture shown in Fig. 1.

Fig. 3 is a left side-view of the fixture shown in Fig. 1.

Fig. 4 is a fragmentary left side-view of the fixture shown in Fig. 1 with the vertical dead-

2

zero stop affixed thereon to determine the vertical position of the swing block, parts being broken away.

Referring now to the drawings in which similar reference characters correspond to the same part or piece in all the different views shown, 1 is the U-shaped base member in which the swing-block or cradle 2 is movable in a 180 degree arc, being held centrally located by the hollow, end-flanged shaft-pieces 3—3 in precision fit graphited bronze-bearings 4—4, which are securely placed in the upper ends of the upright arms of the U-base 1.

In the middle of the swing block 2 a close fitting tool-saddle 5 is movable about a fulcrum-pin 6 so that the diamond holding tool 7 which is held tight in the rectangular opening 8 by two set-screws 49—49 can be put in an angular position.

20 The elongated, curved slots 9—9 and 10—10 correspond to radial sweeps taken from the fulcrum pin 6 and serve the purpose that the tool-saddle 5, which carries the diamond holding tool 7 in its movements, can be securely locked in any angular position to the swing-block 2 with the screws 11—11—11—11.

When a tool-bit is to be used in a lathe or a high production automatic screw-machine to form cut concave or convex radii, such a tool-bit must be form ground with a grinding-wheel into which the respective required radius has first been produced by the diamond holding tool 7, positioned in a precisely calculated setting in the radius-dresser.

35 When a concave or convex radius for a form tool bit is to be cut into the periphery of a grinding wheel with the aid of a diamond holding tool 7, the tool-saddle 5 must be swung on the fulcrum-pin 6 to take on an angular position 1 to 7 degrees from the horizontal zero-line, relative to the rest of the radius dressing unit.

In all cases the preliminary vertical setting of the diamond holding tool 7 itself to its proper height position to cut a certain concave or convex radius into a grinding-wheel periphery is of course calculated and executed while the tool-saddle 5 is in a horizontal zero-line position.

40 To grind a concave or convex contour on a forming-punch and die for stamping purposes the horizontal zero-line setting of the tool-saddle 5 is of course retained when the diamond holding tool 7 is cutting the desired contour into the grinding-wheel periphery.

45 Only when concave or convex contours are to be ground on the ends of tool-bits or multiple

form-tool plates is the tool-saddle 5 shifted a number of degrees and then only after the vertical calculated height setting of the diamond holding tool 7 has first been carried out with the tool-saddle 5 in the horizontal zero-line position.

By shifting the tool-saddle 5 a number of degrees, the diamond tool will cut a concave or convex contour in the periphery of a grinding wheel which would be slightly deformed or at variance with relation to a true precision radius because of the slightly off-center relation of the diamond with relation to the axis of the wheel being dressed.

Now, when this grinding wheel, with the contour which is slightly irregular or deformed as aforesaid, is used to grind a tool-bit, the somewhat deformed contour in the grinding-wheel periphery will, however, grind not only the correct desired concave or convex radius on the tool-bit end, but will also grind the right clearance necessary for the tool-bit to function as a cutting-tool when used on metal parts.

However, one important requirement in this whole procedure should never be overlooked and that is that the tool-bit, when under the contour forming grinding wheel, has to be set-up to exactly the same degree shift position as was applied for the tool-saddle slant in the radius-dressing fixture.

With the ever increasing demand in industry for greater output at lower costs, the exact, correct and right clearance on a tool-bit used in automatic turret lathes and screw-machines can either mean "profit" or "loss."

The absolutely correct perfectly right clearance on a tool-bit means that it is neither too small nor too large.

With the development of special tool-bit steels like stellite and carbide-tipped bits, the clearance cannot be expressed any longer in degrees or fractions of degrees, but in minutes and seconds of degrees, so that it has become imperative to use a sine-bar as the best and most reliable method for setting a radius dressing fixture to grind modern tool-bits to do super-precision work, have great endurance and show no spoilage in long run, high-speed mass production without any tool break-down whatsoever.

Tool-bits with insufficient front-clearance will drag on the work, leaving it rough, uneven and inaccurate.

Tool-bits with too much front-clearance will chatter, leaving marks on the work and cause variations in size. As the cutting-edge is frail, it will wear away too quickly so that continuous resharpening and re-setting becomes necessary.

The many basic metals and alloys in use today, have each and every one their own characteristics as regards state of hardness, ductility, etc. so that a short name: "machinability" is being applied to express in a single term the many, varying degree qualities in all materials known at present.

Once the best front-clearance for a concave or convex form-cutting tool-bit has been found by experimental try and apply methods, notations should be put down on the blue-prints as a guide for the tool-maker in the shop, so that he can set the sine-bar to the precise position on the tool-saddle 5 to duplicate a tool-bit in exactly the same minute detail as was previously found to be performing outstandingly good.

The tool-saddle 5 in this herein presented and fully described novel fixture is therefore provided with sine-bar facilities insofar as an initial or

starting disc 13 is fastened with a set-screw to the revolving fulcrum stud 6 and the second, or measuring-disc 14 is secured to the stud 12 mounted on the saddle 5 in the manner illustrated in Figures 1 and 2. The centre distance between the two discs 13 and 14 gives a five inch sine-bar range, or in other words the disc centers are spaced five inches apart.

The diamond 15 is fused into the holder 7 which is centrally located and held by set-screws in the very close fitting opening 8 in the tool-saddle 5. An elongated rectangular opening 18 is also provided in the middle of the horizontal bar-section of the U-base 1 for the purpose that the diamond holding tool 7 will have sufficient side clearance when the tool-saddle 5 is shifted and used in an angular position.

The diamond holding tool 7 is provided with a precision located pin 19, by the use of which it is possible to set the diamond-tool 7 up for convex grinding-wheel trimming insofar, as it is only necessary to slip a small size block, as for instance the one marked 20 which measures .250 inch, under the pin 19 and which then brings the very top-cutting edge of the diamond 15 one quarter inch (.250 in.) below the horizontal center-line c—d of the whole radius-dressing fixture.

The procedure now in a tool-shop to cut a $\frac{1}{4}$ inch (.250 in.) convex radius, as an example, would be, to bring the radius-dressing fixture which is held tight to the magnetic chuck of the surface grinder, into such a position that the top-cutting edge of the diamond 15 is in the perfect vertical and horizontal center of the grinding wheel 21.

Presuming that the grinding wheel 21 was trued up beforehand, as it should be, and the cutting of a .250 in. convex radius is required, the wheel periphery must be set exactly .250 in. above the cutting edge of the diamond 15 and in this position the reading of the micrometer dial at the hand-wheel of the surface grinder machine which is manipulated to move the grinding wheel toward or from the work should be carefully noted.

With this in mind, the surface grinder is started up and as the wheel is revolving at great speed it is fed slowly down and at the same time the swing-block 2 is continuously moved by hand 90 degrees ($\frac{1}{4}$ turn) to the right and the same distance to the left.

While this is going on, the micrometer-dial at the hand-wheel should be closely watched and when it finally appears that the wheel 21 has been moved .250 in. towards the diamond 15, the surface grinder is switched off and the radius contour, that was cut, is now inspected with precision gages. If the radius in the wheel is found to be satisfactory for the job the radius-dressing fixture is taken off the machine table and the work piece is set up to have the radius that is in the wheel cut into it.

The position the swing-block 2 takes on when it is moved $\frac{1}{4}$ turn to the right, is indicated in Fig. 3 with short dash-lines. When it is moved $\frac{1}{4}$ turn to the left, it is indicated in Fig. 3 with dot- and long dash-lines.

In order that the swing-block 2 cannot in the slightest be moved more than 90 degrees to the right and 90 degrees to the left, a precision stop-plate 22—22 is fastened with flat-head screws 50—50—50 and heavy dowel-pins 51—51—51—51 on top of each upright leg of the U-base 1.

When the swing-block 2 comes to the end of the 90 degree right hand turn, the surfaces

24—24 of the left and right side wing-shaped extensions 23—23 will come in contact with the surface 25—25 of the stop-plates 22—22 in Fig. 1 and Fig. 2. See dotted lines in Figure 3.

When the swing-block 2 now comes to the end of the 90 degree left hand turn, the back of the swing-block 2 will come to rest under the section which overhangs from the stop-plate 22—22 at the spot marked 26 in Fig. 3. See dot and dash lines in Figure 3.

In practice it is often necessary to produce only one corner radius, for which reason it becomes imperative to have a precision stop as vertical zero-rest when the swing block 2 returns from the 90 degree right hand turn.

With the ever increasing demand for super-precision in tool-room work, naturally everything must be of high precision, yet practical and by all means fool-proof, even if it is only a "stop."

Consequently the herein presented vertical dead-zero stop for the described novel radius cutting fixtures should fulfill all reasonable expectations.

One must bear in mind that the fine grinding dust, produced in the action of cutting radii in wheels settles down and of course stays on any flat surface.

The vertical dead-zero stop in the presented invention consists of hardened short rail pieces 27—27, shown in Fig. 1 and Fig. 2. These rail pieces are radius ground so that only very narrow ridges remain at each side of the half-round curves and which are the points of contact with the back of the swing-block 2.

The fine dust that comes off a grinding-wheel when cutting a radius on the periphery cannot cling to the vertical positioned narrow stop-edges of the hardened rail-pieces 27—27 which are held tight in slots provided for that purpose in the support steel-bar 28, which is accurately put in place by dowel-pins 29—29 and securely fastened with filister-head screws 30—30—30—30 to the U-base 1 as shown at the top of Figure 2.

The swing block extensions 23—23 are provided with holes 31—31 in which moves freely the rod 32 shown only in Fig. 2.

The stop-collars 33—33 keep the rod 32 in its assigned position. This also holds true with the handle-bushing 34 which has free rotary movement on the rod 32 and is being held in the desired position by the two collars 35—35.

The end knobbed handle 36 extends approximately 4 inches from the bushing 34 so that, when in practical operation, the swing-block 2 is moved left and right through an arc of 180 degrees, cutting a full half-circle radius in a grinding wheel, the operator's hand is always a safe distance from the wheel, avoiding thereby injuries which have been very prevalent in shops using old style radius-dressers.

In regard to the engraved degree-lines 0 to 7 on the beveled end 55 of the tool-saddle 5, it should be stated that they may be appreciated in some shops where only simple work is done, or in shops where staple articles are made and where all tool-work is standardized over the years, relying in everything on degrees settings.

In some practices it may be found desirable to remove the pivotally mounted saddle 5 and mount a larger diamond tool directly in the large opening 18 in the horizontal bar-section of the swing block 2 and locked in a calculated position by two set-screws 31—37.

In the fixture as shown in the drawings, the physical dimensions are such, that only 6 and 7

inch diameter wheels can be used for convex radii larger than $\frac{1}{2}$ inch. Radii larger than $\frac{1}{2}$ inch are used only for dies and punches, so that a shiftable arrangement like the previously described tool-saddle tilting is not required in this case.

The end-flanged hollow shaft-pieces 3—3 are pinned with precision taper-pins 38—38—38—38 to the swing block 2 in such a way that the holes through the center of shaft-pieces 3—3 remain clear and free. The holes through the center of the shaft-pieces 3—3 serve the purpose of permitting a 12 inch long, round, close fitting shaft to be pushed through for the purpose of checking with sensitive indicators the precision alignment relative to the base and the two sides of the fixture.

The irregular line 39 around the view in Fig. 2 indicates the existence of the magnetic chuck 20 on which the novel radius-dressing fixture in Fig. 2 is held tight and, being supported by four magnetic parallels 40—40—40—40, is lined up square to the ways of the machine against the back-stop 41 which is a stationary part of the 25 magnetic chuck and is set in position with a sensitive indicator.

The four threaded bottom-holes 42—42—42—42 in the U-base 1 are for the purpose to fasten the support-platen O, shown in Fig. 3, to the 30 novel radius-dressing fixture and thereby increasing the hold on the top-surface of the magnetic chuck and any existance of any top-heaviness of fixture as a whole is also, at the same time, reduced to a minimum; perhaps even completely overcome.

Perfectly in the centre of the horizontal bar of the U-base 1 a precision slide-plug is held by the set-screw 48 in the hole 45. The slide-plug can be pushed into a corresponding hole 46 in the 40 swing-block 2 through a smaller hole 47 below hole 45. Pushing the slide-plug upward a short distance into the hole 46 but letting the major portion of its length remain in the hole 45, then by tightening the set-screw 48 on a flat provided in the slide-plug the two main parts of the fixture, namely the U-base 1 and the swing-block 2 are within themselves in an immovable position. This can be most readily utilized by inserting any kind of a pointed diamond tool into the rectangular opening of the tool-saddle 5 and lock the diamond-tool in a handy position.

Now the grinding-wheel can be quickly and easily trued up in preparation for a radius-cutting operation.

This truing-up, pointed diamond tool is now removed from the tool-saddle 5 and with the aid of a wooden drift the slide-plug is pushed back into its seat in the hole 45 in the swing block 2 and locked in its seat by the set-screw 48.

While I have illustrated and described my invention with some degree of particularity, I realize, that in practice various alterations there-in may be made.

Having thus described my invention, what I claim as new and desire to secure by United States Letters Patent is:

1. In a device of the character described, a U-shaped base member comprising a base portion and a pair of support arms extending in parallel spaced relation from said base portion and in perpendicular relation thereto, a U-shaped swing-block comprising a base portion and a pair of mounting arms extending in parallel spaced relation from said swing-block base portion between the base member arms, bearing means

swingably supporting the swing-block arms on the base member arms, the spacing of the swing-block arms providing a central space between said swing-block arms in which to accommodate projection of a work piece, a diamond carrier, a cutting diamond on said carrier and projecting therefrom into the space between the swing-block arms, means supporting said carrier on the swing-block base portion between its arms and in position for engaging with a work piece as the swing-block is swung on its bearing support, each said swing-block arm having stop wing means projecting laterally therefrom, each said base member arm carrying a stop projection engageable by the stop wing means as the swing-block is swung laterally in one direction and by the swing-block arms as the swing-block is swung in the opposite direction to limit the swing-block to a maximum of 180° of swing movement, and handle means extending lengthwise between the wing means at the respective ends of the swing-block and manually operable for imparting swinging movement to said swing-block.

2. A device as defined in claim 1 in which the handle means comprises a rod extending between and attached at its ends to the wing means at the respective ends of the cradle, and a handle rod pivoted to the rod intermediately of its ends and projecting radially therefrom.

3. In a device of the character described, a U-shaped base member comprising a base portion and a pair of support arms extending in parallel spaced relation from said base portion and in perpendicular relation thereto, a U-shaped swing-block comprising a base portion and a pair of mounting arms extending in parallel spaced relation from said swing-block base portion between the base member arms, bearing means swingably supporting the swing-block arms on the base member arms, the spacing of the swing-block arms providing a central space between the swing-block arms in which to accommodate projection of a work piece, a diamond carrier, a cutting diamond on said carrier and projecting therefrom into the space between the swing-block arms, means adjustably supporting said carrier on the swing-block base portion between its arms for movement of adjustment in a direction perpendicularly with relation to the swing axis of the swing-block mounting and in position for engaging with a work piece as the swing-block is swung on its bearing support, the bearing supports for the swing-block arms having a common axis with which the swing-block base portion bears parallel spaced relation, and said carrier supporting means including a saddle to which the carrier is attached, pivot means mounted on the swing-block base portion adjacent one of the swing-block arms and swingably supporting the saddle on the swing-block base portion so that it can be swung relatively to the swing-block base portion to vary the angle of projection of the carrier and the carried diamond with relation to a work piece projecting into the space between the swing-block arms, and clamping means adjustably clamping the saddle against the swing-block portion and securing positions of adjustment of the saddle on the swing-block base portion.

4. A device as defined in claim 3 in which the saddle extends along approximately the full length of the swing-block base portion and is swingably mounted at one of its ends on said swing-block base portion.

5. A device as defined in claim 3 in which the

saddle extends along approximately the full length of the swing-block base portion and is swingably mounted at one of its ends on said swing-block base portion, and wherein the free end of the saddle and the adjacent portion of the swing-block base portion are equipped with cooperating scale means effective to determine adjustments of the saddle on its swing mounting.

6. A device as defined in claim 3 in which the saddle extends along approximately the full length of the swing-block base portion and is swingably mounted at one of its ends on said swing-block base portion, and wherein there is included a cylindrical sine bar receiving disc projecting laterally from each end of the saddle, one said disc being disposed concentrically with relation to the swing center of the saddle.

7. A device as defined in claim 3 in which the saddle extends along approximately the full length of the swing-block base portion and is swingably mounted at one of its ends on said swing-block base portion and inverted U-shaped in cross section so as to straddle the swing block base portion throughout substantially the full length thereof.

8. A device as defined in claim 3 in which the saddle has a gaging surface thereon beside the carrier, and the carrier has a gaging surface overlying the first mentioned gaging surface so that by insertion of a selected gage block between said gaging surfaces the desired degree of projection of the diamond beyond the gaging surface of the saddle can be accurately determined.

9. A device as defined in claim 3 in which the carrier is adjustably supported on the saddle so that the degree of projection of the diamond into the work piece receiving space can be varied, the saddle having a gaging surface thereon beside the carrier, and the carrier having a cylindrical pin projecting laterally from the carrier and providing a gaging surface overlying the first mentioned gaging surface so that by insertion of a selected gage block between said gaging surfaces the desired degree of projection of the diamond beyond the gaging surface of the saddle can be accurately determined, said carrier being rectangular in horizontal cross section and snugly fitted in a receiving recess in the saddle, and said pin projecting at opposite sides of the carrier so that the carrier is mountable with either pin end projecting in either lateral direction.

10. A device as defined in claim 3 in which the saddle and the swing-block base portion each has a recess in which to receive and support the diamond carrier, said saddle being removable to expose the swing-block base portion recess when the same is to serve as a mounting for the diamond carrier, and means engaging the swing-block base portion directly beneath the center of the diamond being included for securing the swing-block against swinging movement on its trunnion mounting.

11. A device as defined in claim 1 in which the stop projection projects into the path of travel of the swing-block from the top of each base member arm and includes an upright portion engageable by the stop wing means and a stop surface engageable by the respective swing-block arm and which is downwardly directed so that foreign matter which might interfere with accurate stopping of the swing-block swing movement cannot readily collect thereon.

12. A device as defined in claim 1 in which there is also included a member removably at-

tached to the base member base portion and having stop members projecting therefrom for engagement by the swing-block base portion when it is desired to limit swing movement with the diamond directed vertically, said stop members being so spaced with relation to the stop wing means engageable stop projection as to co-operate therewith in limiting the swing-block to 90° of movement.

13. A device as defined in claim 1 in which there is also included a member removably attached to the base member base portion and having stop members projecting therefrom for engagement by the swing-block base portion when it is desired to limit swing movement with the diamond directed vertically, said stop members being so spaced with relation to the stop wing means engageable stop projection as to co-operate therewith in limiting the swing block to 90° of movement, each said stop member being 20 shaped to present sharp edge portions for stop contact with the swing-block base portion so that no foreign matter can collect on the stop members in position for interfering with accurate stop contact with said swing-block base 25 portion.

14. In a device of the character described, a U-shaped base member comprising a base portion and a pair of support arms extending in parallel spaced relation from said base portion 30 and in perpendicular relation thereto, a U-shaped swing-block comprising a base portion and a pair of mounting arms extending in parallel spaced relation from said swing-block base portion between the base member arms, bearing means swingably supporting the swing-block arms on the base member arms, the spacing of the swing-block arms providing a central space between said swing-block arms in which to ac-

commodate projection of a work piece, a diamond carrier, a cutting diamond on said carrier and projecting therefrom into the space between the swing-block arms, said bearing means including a bearing pin secured to and extending through the upper end of each swing-block arm, each said pin having a bearing body rockably mounted in a bearing bore in the adjacent base member arm and an enlarged head outside the respective bearing bore at the side of the base member arm remote from the adjacent swing-block arm, and said bearing pins having axially aligned center bores extending therethrough to receive a close fitting shaft which may serve as a part of precision aligning equipment.
